UNITED STATES PATENT OFFICE.

CHARLES BARREZ, OF PARIS, FRANCE.

MACHINE FOR THE AUTOMATIC MANUFACTURE OF BLOWN-GLASS ARTICLES.

964,198.

Specification of Letters Patent. Patented July 12, 1910.

Application filed August 2, 1907. Serial No. 386,849.

To all whom it may concern:

Be it known that I, CHARLES BARREZ, a citizen of the Republic of France, residing at Paris, France, have invented certain new and useful Improvements in Machines for the Automatic Manufacture of Blown-Glass Articles, of which the following is a specification.

The present invention relates to improvements in machines for the automatic manufacture of articles of blown glass, bottles, etc., and is chiefly characterized 1. by the method of automatic opening and closing of the ring-mold, the workman thus not having to attend to the manipulation of the mold, which results in the economy of movements, reliability and rapidity of the manufacture. 2. by the easy and adjustable manipulation of the "punch" intended for closing the ring-mold and the admission or inlet for air for blowing. 3. by the very simple method of opening and closing the molds, raising and lowering the bottom and the compressor, these movements being brought about simply by the manipulation of a cock for distributing and discharging compressed air. 4. by the use of a permanent perforating bottom and the rotation of bottles on the machine itself. 5. by the use of various accessory parts, such as a perforated or non-perforated cup with air circulation, the cup being capable of rotating about the blank, cooling devices, extractors of finished bottles, all the above parts reducing the movements of the attendant, or enabling the manufacture to be otherwise improved or simplified. 6. by the whole of these combinations which make this machine an entirely new machine in which the work of the attendant is reduced to a minimum, thereby making the manufacture more reliable and enabling the output to be increased.

A machine according to this invention is illustrated in the accompanying drawings, in which:

Figure 1 is an elevation of the machine partly in section; Fig. 2 a side elevation parts being in section; Fig. 3 a view of the rough-shaping parts and of the ring-molds; Fig. 4 a view of the ring-mold inverted, and of the finishing mold; Fig. 5 a view of the finishing mold showing the method of opening the ring-mold; Fig. 6 a view of the parts for recessing the bottoms of the bottles and the method of making the "kick" or re-

cess; Fig. 7 another shape of the part for recessing the bottom of the bottle; Fig. 8 a view of the air circulation cup used for working the blank; Fig. 9 a view of some of the different shapes of the cooling devices for the blanks and the molds; Figs. 10 and 11 are views of the bottle-removing device.

On the frame 1 are mounted: 1. Up- rights 2 supporting the cylinders 3 and 4 and the spindle supporting the ring-mold. 2. The bottom 6 of the finishing mold. 3. The distributing device 7. 4. The supports for the cylinders 3 and guide rods 8 connected to the two parts constituting the rough-shaping mold 9. These rods control both its opening and closing.

The supports for the cylinders 4 and guide rods 10 connected to the two parts constituting the finishing mold 11, and controlling its opening and closing.

The closing of the rough-shaping and finishing molds is effected by means of compressed air supplied by the cock or valve 7 80 and acting on one of the faces of a piston 12, while the opening is effected by the discharge of the air and the pressure of the springs 13.

The ring-mold supporting spindle 5 is 85 provided with a hand-wheel 14 enabling the ring mold to be turned.

The raising of the bottom 6 is effected by means of compressed air acting on a piston 15 provided with a return spring 16. 90

The ring-mold 17 consists of two parts secured to rods 18 adjustable in brackets 19 forming one piece with a part 20 secured to the supporting spindle 5.

Lugs or tappets 21 enable the ring-mold 95 to be automatically opened and closed.

Stops 22 are secured to the two upper halves of the finishing mold 11 for effecting the opening of the ring-mold.

The recessed cylinder 23, supported by the 100 spindle 5, receives the ring-mold 17 and serves for receiving a punch 24.

A hand-wheel 25 serves for manipulating the valve 7 for opening and closing the molds and raising the bottom.

A pedal 26 controls the admission of air for blowing the bottle.

Semi-circular shoulders 27 of the rough-shaping mold serve for automatically closing the ring-mold.

A handle 28 serves for raising the punch returned by the spring 29.

- 30 is a collar of the punch.
 31 (Fig. 2) is the blowing air inlet.
 32 (Fig. 1) is the compressor.
 33 (Fig. 6) is a cast iron casing for the
 5 bottom of the bottle when being recessed.
 34 is the refractory clay bottom.
 35 is a recessing device operated by a
 handle 36 which raises it by means of a
 lever 37 arranged in a hole 38 in the recess-
 10 ing device.
 The recessing device can be provided with
 perforations through which air could be ad-
 mitted under the blank.
 39 (Fig. 8) is a cup serving for support-
 15 ing and lengthening the blank, cooled at
 given places by means of one or more con-
 duits 40 in which circulates cold air sup-
 plied through the hollow handle 41 and
 escaping at 42.
 20 43 are perforations in the bottom of the
 cup. These perforations are made only in
 certain cups intended to be used for perfor-
 rating or strongly cooling the bottom of the
 blank.
 25 44 45 are different shapes of sprayers for
 directing air against certain portions of the
 blank or for cooling the ring-mold etc.
 46 is the leg of the apparatus for extract-
 ing the bottles.
 30 47 to 55 are various parts of the apparatus
 serving for removing the bottles from the
 machine.
 Air-inlet pipes connect the cylinders for
 35 manipulating the molds and the bottom to
 the distributing cock, and are arranged as
 may be thought advisable, or concealed in
 the frame.
 The working of the machine is as fol-
 lows:—The ring-mold 17 being in its upper
 40 position (Fig. 1) the attendant turns the
 hand-wheel 25 operating the cock 7, and air
 is admitted against the pistons 12 of the
 cylinders 3, thus closing the rough-shaping
 mold 9 by forcing inward the rods 8. At
 45 the same time, the two halves of the ring-
 mold 17 are also driven inward by the two
 semi-circular shoulders 27 on the inner face
 of the two halves of the rough-shaping mold,
 and the two molds are thus closed (Fig. 3)
 50 without any possibility of accident due to
 forgetfulness, and by a single operation per-
 formed by the attendant of the machine.
 The two mold-halves having been closed, the
 attendant, by means of the handle 28 (Fig.
 55 2) raises the punch 24 arranged in the cylin-
 der 23. The workman attending to the
 ladling then pours the glass into the rough-
 shaping mold and into the ring-mold 17.
 A fork, not shown in the drawing, can be
 60 provided on the machine for enabling him
 to support his blowing pipe during the pour-
 ing of the glass. The compressor 32 is then
 operated, if desired, then the attendant re-
 leases the handle 28, and the punch 24 is
 65 returned to its original position by the

spring 29. The descent of the punch is lim-
 ited by the collar 30. At the same time he
 turns the hand-wheel 25 in order to allow
 air to escape from the cylinders 3, and there-
 by to open the rough-shaping mold 9 by 70
 means of the springs 13. At the same mo-
 ment he presses on the pedal 26 and air for
 blowing the bottle penetrates into the mass
 of glass through the conduit 31 (Fig. 2)
 made in the cylinder 23 at the side of the 75
 punch head 24. The blowing continuing
 slightly, and the blank being released from
 the rough-shaping mold 9, the attendant
 turns over the ring-mold and the blank by
 manipulating the hand-wheel 14, and the 80
 spindle 5 (Fig. 4) the blank supported then
 by the ring-mold coming between the two
 parts or halves of the finishing mold 11. At
 that moment the attendant, by means of a
 sprayer 44 45, directs cooling air against 85
 any portions of the blank which he thinks
 advisable, at the same time shaping the
 blank with his spoon or cup 39 and cooling
 it, lengthening or perforating according as
 may be required by the work and by the ob- 90
 ject to be attained. The sprayer, in view of
 its different shapes, could also be used for
 cooling different parts of the machine, such
 as the ring-mold, etc. The blank thus hav-
 ing been brought to the desired state, the at- 95
 tendant again turns the hand-wheel 25 of
 the cock 7, and the air admitted under the
 piston 15, raises the bottom 6 (Fig. 4), then,
 by continuing to turn the hand-wheel 25, he
 admits air to the pistons 12 of the finishing 100
 mold and closes the latter which then sur-
 rounds the blank. During all these manip-
 ulations the attendant continues to blow the
 blank, and as soon as the finishing mold is
 closed and surrounds the blank, he blows 105
 more energetically, always by means of the
 pedal 26. When the blowing is completed
 the attendant opens the finishing mold 11 by
 releasing the air behind the piston to allow
 the spring 13 to act; the finishing mold, on 110
 opening, opens the ring-mold and com-
 pletely releases the bottle which then rests
 on the raised bottom 6.

The opening of the ring-mold by the fin-
 ishing mold is effected by means of the stops 115
 22 which come into contact with the tappets
 21 during the opening movement of the
 finishing mold, the rods 19 for manipulating
 the ring-mold sliding them in their supports
 17 (Fig. 5).

As already stated, the bottle is supported
 freely on the bottom 6, so that a boy has
 merely to take it and transport it to the
 annealing furnace. The attendant then low-
 ers the bottom 6 by turning the cock 7 to 125
 allow the spring 16 to act; then, by rotat-
 ing in the opposite direction the hand-wheel
 14 of the spindle 5, the open ring-mold is
 returned into the position shown in Fig. 1,
 and the operations hereinbefore described 130

can again take place for the manufacture of another bottle.

In the event of its being desired to make a kick in the mold, the following arrangement could be adopted: Instead of the bottom 6, its supporting rod is provided with a special kick-forming bottom 33 34 (Fig. 6) comprising the bottom proper consisting of a hollow part 34 of refractory clay or 10 other material contained in a cast iron frame 33, the said two parts being provided in the center with an opening for the passage of the recessing device 35. This bottom being in place, and the finishing mold closed 15 and containing the blank, the attendant presses on the handle 36, which raises the recessing device 35 through the clay bottom, and penetrates into the blank, forcing back the glass, and at the same time he 20 imparts to the bottom, by means of the same handle, a turning movement of about three-quarters of a revolution, then he releases the handle 36 wherupon the bottom is recessed and finished and it only remains 25 to open the finishing mold as hereinbefore described.

The recessing device instead of being operated by hand, could also be operated automatically, and the shape of the recessing 30 device and of the clay bottom can also vary in accordance with the shapes to be obtained.

The spoon or cup (Fig. 8) used for supporting and working the blank as hereinbefore described, could in certain cases be provided with perforations in the bottom, the said perforations making possible a more energetic cooling of the blank or even, in the manufacture of certain articles, enabling 35 their bottom to be perforated or indented. Naturally the inner shape of the said cup or spoon will vary in accordance with the shape of the articles to be treated.

The bottle having been completed, and 40 the finishing mold opened, the bottle, instead of being removed by a boy as stated, could be withdrawn from the bottom by an automatic bottle extractor shown in the drawings in Figs. 10 and 11 in elevation and plan. This apparatus comprises an arm 46 secured to the machine and supporting a pipe or tube 47 movable on the said arm, a spring 48, a curved arm 49 secured to the tube and provided at the end with 45 a fork or gripper 50 intended to seize the bottle under the ring. This fork could be provided with an opening and closing motion for better seizing and holding the bottle. The working of this apparatus is as 50 follows:—The bottle having been completed, the attendant opens the finishing mold provided (when the said apparatus is used) on one of its halves with a stop 51 which, at the opening of the mold, strikes a tappet 55 52 (Fig. 11) which partly rotates the tube

47 and consequently the arm 49 describes a circular and rectilinear movement which brings the gripper 50 exactly under the ring of the bottle and causes it to embrace it tightly. When the attendant lowers the 70 bottom supporting the manufactured bottle, the bottle remains suspended in the gripper 50, (Fig. 10), but at the moment when the bottom arrives at the end of its travel, it meets a pedal or lever 53 which, by raising a rod 54, releases the whole movable part of the extractor, that is to say, the tube 47, the curved arm 49, the gripper 50 and the bottle supported by it, and the whole, operated by the spring 48, turns, and the 80 bottle is thus automatically removed from the bottom without the attendant having to attend to it. It is then removed from the gripper 50 either by striking a stop 55, or by the boy himself. 85

What I claim as my invention and desire to secure by Letters Patent is:—

1. In a machine for making bottles or other hollow articles of glass the combination with divided rough-shaping and finishing molds, supports therefor, a source of compressed air, a pair of oppositely-arranged cylinders adjacent the parts of the rough-shaping mold, a pair of oppositely-arranged cylinders adjacent the parts of the finishing 90 mold, a reciprocable piston in each of the cylinders, rods connected with the pistons and with the parts of the rough-shaping and finishing molds as set forth, a spring within each cylinder arranged to act upon each of 100 the pistons, a regulating cock adapted to regulate the flow of the compressed air, and connections between the said cock and the respective cylinders, of a movable divided ring-mold arranged in the path of the closing movement of the parts of the rough-shaping mold and adapted to be operated thereby so as to close as described, and means intermediate the ring-mold sections and the parts of the finishing mold whereby said 110 ring mold will be opened by the opening movement of the parts of the finishing mold. 105

2. In a machine of the character described, the combination with rough-shaping and finishing molds each comprising movable 115 parts, of a finished bottle transporter comprising an upright arm, a tube movable on said arm, a spring acting upon said arm, a curved arm secured to the tube, a bottle-neck gripper carried by said curved arm, a tappet 120 on the tube, and a stop on one of the parts of the finishing mold adapted to strike said tappet.

In testimony whereof I have signed my name to this specification in the presence of 125 two subscribing witnesses.

CHARLES BARREZ.
